UNITED STATES PATENT OFFICE

94,769

DESIGN FOR A ROLLER SKATE

Leland G. Knapp, Chicago, Ill., assignor to Montgomery Ward & Co., Incorporated, Chicago, Ill., a corporation of Illinois

Application November 19, 1934, Serial No. 54,075

Term of patent 7 years

To all whom it may concern:

Be it known that I, Leland G. Knapp, a citizen of the United States, residing at Chicago, in the county of Cook and State of Illinois, have invented a new, original, and ornamental Design for a Roller Skate, of which the following is a specification, reference being had to the accompanying drawing, forming a part hereof.

In the drawing,

Fig. 1 is a top plan view of a roller skate showing my new design; and

Fig. 2 is a side elevation thereof.

I claim:

The ornamental design for a roller skate, as shown.

LELAND G. KNAPP.
